UNITED STATES PATENT OFFICE.

JOHN W. VOGAN, OF PORTLAND, OREGON, ASSIGNOR TO VOGAN CANDY COMPANY, OF PORTLAND, OREGON, A CORPORATION OF OREGON.

DISPLAY AND SALES CONTAINER.

Application filed December 12, 1922. Serial No. 606,460.

To all whom it may concern:

Be it known that I, JOHN W. VOGAN, a citizen of the United States, residing at Portland, in the county of Multnomah and State of Oregon, have invented a new and useful Display and Sales Container, of which the following is a specification.

The present invention relates to a display and sales container, and has particularly to do with a container adapted for use in connection with the sale of candy or other small piece goods.

Among the objects of the invention are, the provision of a container for small unit merchandise which forms substantial protection during the handling thereof and which is quickly removable for displaying the goods for a considerable depth; the production of a simplified box construction for candy and the like; and the supplying of a packing for merchandise such as candy which will admit of instant removal of the enclosing element in order to completely display the contents of the container.

These, and such other objects as may hereinafter appear, are obtained by the novel construction, combination, and arrangement of the several parts of my device, which device is fully described in the accompanying specification, and in the single sheet of drawing, made a part thereof, and in which:—

Fig. 1 is an elevation of my device with the parts thereof in dissociated position;

Fig. 2 is a vertical section of the device with the several parts thereof associated for use as a packing container;

Fig. 3 is a vertical section of the bottom or tray portion thereof after removal of the top or cover and sides or body thereof for displaying the contents; and

Fig. 4 is a horizontal section disclosing a modified form of the device.

Like reference characters are used to designate similar parts in the drawing and the description which follows.

The complete device comprises three parts, namely, a base, bottom or tray; a body, or side portion; and a top or cover.

The ordinal 10 is used to designate the tray or base portion, which is substantially identical in construction with the bottom or base portion of a flanged telescoping candy box, the side walls 11 of the base portion being, in the form disclosed, quite shallow. In

Figs. 2 and 3, candy is shown packed in the device, and it will be noted that the major portion of the merchandise projects well above the shallow walls 11.

Such bottom section 10 may be formed of two thicknesses of material except at its edges, the upper thickness of material extending wholly across the bottom of the box and being bent upwardly to form the side walls 11, while the lower or exterior thickness extends across the bottom of the container and projects outwardly beyond the upper thickness to form flanges 12.

A body or side portion of the box is designated 13 and is in a single continuous strip having the same configuration as the base side walls 11, and is of such size that it will readily slip thereover. The height of the body or sides 13 is considerably greater than that of the side walls 11 of the base 10.

A top or cover 14 for the container, of the slip-over or telescoping type, is provided. The depending side walls 15 thereof provide a snug overset about the side or body 13, so that when the device is completely assembled, it may be said that part 13 telescopes over part 10 and is in turn telescoped by part 14. The depending walls 15 which extend downwardly over body 13 a considerable portion thereof securely reinforce the latter against bulge or rupture.

It is manifest that the shape of the container may not only be rectangular or cylindrical, which shapes are most frequently met in containers for merchandise, but other shapes may be employed without departing from the invention so long as the telescoping effect of the several parts thereof herein described is obtainable.

Pasteboard, wood, or metal may be employed as the material for the construction of my device.

In packing my containers for shipment of merchandise therein, it is customary to place the body portion 13 in position upon the base 10, and dispose units of merchandise therein in such arrangement that such merchandise will remain in undisturbed position upon upward movement of body 13 to displace it from bottom 10. When the container is filled for shipment, the cap or cover 14 is placed thereon, and the container is ready for shipment in the usual way.

Arriving at its destination and a display of the contents therein being desired,

it is usual to first remove the cover 14, and then to carefully remove the body 13 from tray 10, exercising caution not to disturb the arrangement of the goods therewithin 5 and to restore such units of merchandise as have become accidentally displaced in transportation to their original arrangement.

The illustrations in Figs. 2 and 3 clearly indicate how the container may first be employed for packing and later for displaying candy.

In Fig. 4 a slightly modified form of the invention is disclosed. In such modified form the base and cover are identical with 15 the same parts as when employed in the preferred form. The body 13' comprises, in the rectangular form of the modified container shown in Fig. 4, four sections, two of which sections although abutting are not 20 continuous as in the preferred form. It is necessary in packing merchandise in a container having a body portion 13' to hold the free ends of the two disjoined sections together, either manually or by a paster or 25 the like, until the container is filled. The continuous depending flange 15 upon the cover 14, upon seating the cover about body 13', will prevent accidental separation of such free ends. Facility in removing the 30 body portion 13' is of course acquired by such open-ended construction. Compactness in packing of the containers is obtained by such modified form of the device if the body section thereof is high. In

packing, cover 14 may be slid over base 35 10 while the body portion 13' may be packed as a strip material or folded up compactly with one section disposed upon another.

What has been said about compact packing in the modified form of the device is 40 equally true of the preferred form and particularly the rectangular type thereof. The body portion 13 may be flattened out by folding opposite corners thereof at 180° for 45 packing purposes.

I claim:

1. A container for bulk chocolates and the like and of any desired shape, comprising a bottom, a middle and a top section, the bottom section providing a display tray and having an upturned flange away from its margin within the border of which the contents of the container are packed in layers extending above the top of said flange, the middle section encircling said bottom flange and extending thereabove, and the top section having a peripheral flange extending over and downwardly upon said middle section, both said top and middle sections being readily removable to admit of the display of the contents of the container as packed upon said bottom section.

2. A container as described in claim 1, and in which said middle section comprises a strip of sheet material adapted to be held about said bottom section by said top section.

JOHN W. VOGAN.
